UNITED STATES PATENT OFFICE.

PAUL C. KAUFFMAN, OF SEATTLE, WASHINGTON.

DESIGN FOR A MARINE-COMPASS BRACKET.

Application filed March 18, 1924. Serial No. 8,982. Term of patent 7 years.

To all whom it may concern:

Be it known that I, PAUL C. KAUFFMAN, a citizen of the United States, residing at Seattle, in the county of King and State of Washington, have invented a new, original, and ornamental Design for Marine-Compass Brackets, of which the following is a specification, reference being had to the accompanying drawing, forming a part thereof.

In the drawing the figure is a view in perspective of a marine compass bracket showing my new design.

I claim:

The ornamental design for a marine compass bracket as shown.

PAUL C. KAUFFMAN.
